UNITED STATES PATENT OFFICE.

VICTOR M. SUMMA, OF ST. LOUIS, MISSOURI, ASSIGNEE TO AMERICAN CAR AND FOUNDRY COMPANY, OF ST. LOUIS, MISSOURI, A CORPORATION OF NEW JERSEY.

RAILWAY-CAR.

1,102,605.

Specification of Letters Patent. Patented Sept. 1, 1914.

Application filed July 21, 1913. Serial No. 786,803.

To all whom it may concern:

Be it known that I, VICTOR M. SUMMA, residing at St. Louis, Missouri, and being a citizen of the United States, have invented 5 certain new and useful Improvements in Railway-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact 10 details of construction shown and described, as it is obvious that various modifications thereof will occur to persons skilled in the art.

The principal object of the invention is to provide an underframe of structural 15 shapes throughout and having few parts so that the labor and expense involved in assembling, repairing or replacing the different parts will be materially reduced.

One object is to provide an underframe 20 in which all of the members are rigidly connected and which are so arranged that the removal and replacement of a damaged cross beam or a longitudinal member may be easily effected.

25 A further object is to provide direct cross beam support for the superstructure at points between and outside of the side sills whereby the superstructure is positively secured against lateral shifting upon the underframe. This advantage results from the extension of the cross beams through openings in the side sills, the protruding ends of the cross beams providing supports for the floor nailin^g sills which extend outside of 30 and parallel with the side sills, thus dispensing with hangers commonly employed for this purpose.

Owing to the intimate connection of the 35 parts, the underframe acts as a unit in resisting stresses tending to distort or unduly strain any one portion thereof. The interlocking continuous members operate to distribute the load imposed over the effective underframe area. An underframe constructed in accordance with this invention provides a rigid, self-contained structure of 40 uniform strength throughout and adapted

to operate as a column in resisting buffing shocks.

The invention consists further in the 55 means employed for practically accomplishing the above objects, as shown particularly in the drawing in which—

Figure 1 is a plan view of an underframe embodying the invention. Since both ends of the underframe are similar, one-half only of the structure is shown for convenience of illustration, with parts broken away to more clearly show the manner of connecting the different parts. Fig. 2 is a side elevational 60 view of the same. Fig. 3 is a vertical section through the bolster taken on line 3—3 of Fig. 1, showing the application of the bolster reinforcement and the method of assembling the center plate therewith. Fig. 4 65 is a section through one of the cross beams intermediate the bolsters taken on line 4—4 of Fig. 1 showing the method of securing said members to the longitudinal sills of the underframe. Fig. 5 is a transverse vertical 70 section through the underframe at the bolster, partly on line 5—5, Fig. 1, with some parts broken away to illustrate additional details. Fig. 6 is a similar view at one of the intermediate cross beams, partly on line 75 5—6, Fig. 1, with some parts broken away to illustrate additional details. Fig. 7 is a similar view showing the application of the invention to an underframe of the single center sill type. Figs. 8, 9 and 10 illustrate 80 the manner of attaching the superstructure framing of a car to an underframe built in accordance with this invention, and show respectively a horizontal section through a portion of the framing at one of the cross beams, a side elevation thereof, and a transverse section through the same. Fig. 11 85 shows a section through a modified form of cross beam of channel shape in section connected to the inner face of the side sill member of the underframe. Fig. 12 is a side elevational view of a further modification showing the application of the invention to an underframe having side sills of pressed 90 plate. Fig. 13 is a transverse section taken 100 through the same showing the manner of assembling the cross beams and nailin^g stringer support therewith. Fig. 14 is a composite view similar to Figs. 5 and 6,

showing a modified form of construction in section, as on line 5—5, one center sill and one side sill and as on line 6—6 a center and side sill with a cross bearer in elevation, the 5 section lines being indicated on Fig. 1.

In the drawings, A represents the center sills which, in practice, are preferably continuous from one end sill to end of the car, but it is obvious that they may terminate 10 short of the car end if desired and separate draft sill members may be spliced thereto at points adjacent the bolsters. These longitudinal sills may be of any type, but rolled sections are preferred because of their 15 peculiar adaptability to the invention: B represents the side sills which also are preferably of rolled section; C the end sill; D, the central floor nailing sill; E, the intermediate floor nailing sills; F, the side floor nailing sills; G, the bolsters preferably of rolled 20 shape and of constant cross section; H, the intermediate cross beams, also preferably of rolled section; J, represents the cross beam chairs shaped to the contour of the beam and secured thereto by rivets 2 and to the longitudinal sills A and B of the underframe by 25 rivets 1.

Brackets K are arranged on opposite sides of the bolsters and between the center sills, and are secured by rivets 9 passing through bracket flanges 11 and center sills A, and by rivets 10 connecting bracket walls 12 to bolster web 13. These brackets and lower face of bolster beam G, provide an extended bearing for securing the center plate L. These parts are secured by means of rivets 3 connecting bracket flanges 4 and center bearing flanges 5. The center bearing L is further secured by rivets 8 connecting auxiliary flanges 6 to center sill flanges 7. The projecting ends of the cross beams provide seats 14 for the floor nailing sills F which are secured against displacement by means of bolts connecting same to short angle 40 pieces M arranged at points between the cross beam and near each end sill.

When superstructure framing is applied to the underframe as in Figs. 8, 9 and 10, floor nailing sills F will be positioned on the cross beams at points adjacent the inner side of the side sills as shown in Fig. 10, and framing post 15 secured to the protruding end 16 of the cross beams by rivets 17 passing through web 18 of the post, the web of 50 the cross beam and flange 19 of connection plate 20 connecting post 15 to diagonal brace 21 by rivets 22, 23 and 24. The posts 15 and braces 21 are also secured to side sills by rivets 25 and 26 respectively. In such 55 construction it is advisable to place the socketed castings or cross beam chairs J on the inner sides of the side sills and secure them in such position, as shown in Fig. 11, if such members J are used, although it will be evident from an inspection of Figs. 8, 9 and 10

that where side posts or diagonals lap the outer unflanged sides of said center sills, said side posts and diagonals, either or both, may be connected with the side sills and to the protruding ends of the cross-bearers, in which case the members J need not be employed at the side sills. For convenience of assembling the parts, said socket castings or chairs J are preferably left open, as shown. When, for any reason, the side sills are not perforated and the cross-bearers are not extended through said side sill perforations, the socket castings J, connected to the inner faces of the side sills, will be interlocked with the continuous cross-bearers by means of the rivet connection best shown in Fig. 4, and the side sills will be connected to the outer ends of said cross-bearers by means of said socket castings. Thus spreading of the side sills will be prevented and, under normal conditions, the side sills may support the center sills, or the center sill may support the side sills, depending upon which is the stiffer and on the disposition of the load in the car.

When pressed side sills are used as shown in Figs. 12 and 13, the Z-shaped bars 27 thereof rest upon the nailing sill supports 14 secured thereto and to the sill B by rivets 28 and 29 respectively; the inwardly projecting upper flange 30 of the Z-bar 27 constitutes the top chord of the side sill member, while lower flange 31 carries the nailing sill F.

It will be noted that the cross beam ends 100 find a bearing in brackets J secured to the side sill, whereby any tendency to vertical movement thereof in either direction is amply resisted by the side sill.

Where, for any reason, it is considered 105 undesirable to use a continuous rolled section for a bolster, the bolster construction shown in Fig. 14 may be substituted, which bolster is of conventional form employing the pressed diaphragms 35, preferably 110 flanged on all of their edges and connected by top and bottom cover plates 36 and 37, the top cover plate 36 extending through slots in the center sills and the bottom cover plate 37 extending below the center sills, 115 with the center bearing plate 38 secured to the bottom cover plate 37, the bottom flanges of the center sills and to an intermediate filler 39, which may be of any convenient contour adaptable to the purpose.

Heretofore it has been found necessary where continuous cross bearers are employed projecting through the webs of center sills, to elevate the side sills above the upper plane of said cross bearers to facilitate removal and replacement of the cross bearers.

In many types of box cars it is desirable to lower the center of gravity as much as possible, and for that purpose, as well as for convenience of assembling and to pro-

vide a more perfect buffing column, the present arrangement is substituted, in which substantially all the longitudinal and transverse members of the underframe are connected and carried in relatively the same planes and are easily removable for repairs and replacements.

With the side sills perforated, as shown, for the passage of the transverse members of the underframe it is convenient to position the side sills much nearer the rail than is, as shown, for example in Keithley Patent 307,701, the side sills are carried upon the outer ends of the cross bearers.

13. As the bolster shown in Fig. 14 is built up of separately formed parts, it is evident that said bolster may be removed entirely or in part without displacement of the side sills. The bolster construction illustrated in Figs. 2 and 3 includes a center bearing plate which is secured directly to the center sills and is connected by the intermediate filler castings shown best in Fig. 3, not only with the ends of the bolster but also with the webs of the under sills, whereby a rocking tendency of the bolster, due to buffing stresses, is eliminated.

The bracket castings employed for connecting the transverse members of the underframe with the side sills are so arranged that rivets may extend through the webs of the transverse members and through the webs of the side sills, thereby securely tying said parts together and better adapting them to resist outward deflection due to buffing stresses which, as will be noted, are resisted by all the longitudinal members of the underframe, due to the intimate connection of the transverse members therewith. Likewise, the bracket castings connecting the center sills with the transverse members and the bracket castings connecting the side sills and transverse members are adapted to connect with center sills and transverse members, whereby buffing stresses will be, to a great extent, absorbed in the central longitudinal portion of the underframe, leaving only a part of the stresses to be transmitted to the side sills, which stresses are amply resisted by the connection of side sills and transverse members, before indicated.

I claim:

1. In a car underframe, a center sill, spaced side sills and continuous cross bearers held in interlocking engagement with all of said sills by penetration of and connection therewith.

2. In a car underframe, a center sill, spaced side sills and continuous rolled cross bearers of constant section held in interlocking engagement with all of said sills by penetration of and connection therewith.

3. In a car underframe, a center sill, spaced side sills and a continuous rolled cross bearer penetrating said sills and being

supported thereby near its middle portion and near its opposite ends.

4. In a car underframe, continuous spaced side sills, center sills, and cross bearers penetrating all of said sills and connected rigidly therewith to form a buffing column the entire width of the underframe.

5. In a car underframe, a center sill, a longitudinal sill at each side of said center sill in a plane therewith, a plurality of continuous cross bearers penetrating and connected with all of said sills, and means rigidly connecting said parts.

6. In combination, a rolled plate girder center sill, side sills and rolled continuous cross bearers all in substantially the same plane and inter-connected by penetration so as to be readily separable.

7. In a railway car, bolsters, side sills continuous between said bolsters, and continuous cross bearers extending in the plane of and removable as units through said side sills.

8. In a railway car, bolsters, side sills continuous between said bolsters, and continuous cross bearers of relatively constant section extending in the plane of and removable as units through said side sills.

9. In a railway car, bolsters, side sills continuous between said bolsters, continuous cross bearers extending in the plane of and removable as units through said side sills, and side framing members connected to said side sills and to said cross bearers.

10. In a railway car, side sills, cross bearers penetrating said side sills, and side framing members connected directly to said cross bearers at the outer side of said side sills.

11. In a car underframe, center sills, side sills and cross bearers in substantially the same plane, the cross bearers projecting through the side sills, and side framing members connected to said cross bearers and to said side sills.

12. In a car underframe, continuous rolled center sills, side sills and transverse members all substantially in the same plane and all interconnected by penetration of the webs of some of said members by other members extending at substantially right angles thereto.

13. In a car underframe, center sills, side sills and transverse floor supporting members in substantially the same plane, the transverse members being removable as units by movement thereof transversely of said underframe through said side sills.

14. In a car underframe, spaced side sills with apertures therein, an apertured center sill, and a continuous cross bearing member extended through said apertures.

15. In a car underframe, spaced side sills with apertures therein, an apertured center sill, a continuous cross bearer in the plane of

of and projected through said apertures, and a side framing member secured directly to said cross bearer.

16. In a car underframe, a center sill comprising spaced vertical web portions, spaced side sills and a continuous cross-bearing member held in interlocking engagement with said center and side sills by penetration of the webs of said sills and by connection therewith.

17. In a car underframe, spaced side sills and an intermediate center sill provided with aligned apertures, a continuous cross bearer in said apertures projecting beyond said side sills, and pocket castings connecting the sills and cross bearer.

18. In a car underframe, spaced side sills provided with aligned perforations, a continuous cross bearing member projected through said perforations and beyond said sills, and a body framing member connected directly to said cross bearing member outside of said sills.

19. In a car underframe, spaced side sills provided with aligned perforations, a continuous cross bearing member projected through said perforations and beyond said sills, and a body framing member connected directly with said sills and said member.

20. In a car underframe, spaced side sills provided with aligned perforations, a continuous cross bearing member projected through said perforations and beyond said sills, and a body framing member connected directly to the webs of said sills, one of said framing members being connected to the cross bearing member, and a connection plate uniting said framing members.

21. In a car underframe, spaced side sills and spaced center sills provided with aligned apertures, a continuous cross bearer, and pocket castings connected directly to the webs of all of said sills and the cross bearer.

22. In a car underframe, a center sill, spaced side sills, body posts on the outer sides of said sills, and continuous cross-bearers held in interlocking engagement with said center sill by penetration thereof, and by connection therewith and with said body posts.

23. In a car underframe, a center sill, spaced side sills, body posts and diagonals, and continuous cross-bearers held in interlocking engagement with said center sill by penetration thereof and by direct connection to said posts and diagonals.

24. In a car underframe, a center sill, spaced side sills, body framing members lapping said side sills, and a continuous cross-bearer penetrating said sills and being supported thereby, and near its ends being connected to said body framing members.

25. In a car underframe, continuous spaced side sills, a center sill, body framing members lapping said side sills, and a cross-

bearer penetrating all of said sills and connected with said body framing members.

26. In a car underframe, a center sill, a side sill at each side of said center sill in a plane therewith, body framing members lapping said side sills, a plurality of continuous cross-bearers penetrating and connected with all of said sills, and means rigidly connecting all of said parts.

27. In combination, a plate girder center sill, side sills and continuous cross-bearers all in substantially the same planes, and body framing members connected with said side sills and with said cross-bearers.

28. In a railway car, bolsters, side sills continuous between said bolsters, body framing members lapping said side sills, continuous cross-bearers extending in the plane of and being connected at their outer ends with said body framing members.

29. In a railway car, bolsters, side sills continuous between said bolsters, continuous cross-bearers extending in the plane of and through said side sills, and floor-nailing sills supported on said cross-bearers on the outer sides of said side sills.

30. In a railway car, bolsters, side sills continuous between said bolsters, continuous cross-bearers extending in the plane of and projecting beyond said side sills, and side framing members connected to said side sills and to said cross-bearers.

31. In a railway car, side sills, cross-bearers penetrating said side sills, and floor-nailing sills supported on the outer ends of said cross-bearers at the outer side of said side sills.

32. In a car underframe, a center sill, side sills and cross-bearers in substantially the same planes, the cross-bearers projecting through the side sills, and floor-nailing sills resting on portions of said side sills above said cross-bearers and receiving support from said sills and cross-bearers.

33. In a car underframe, continuous center sills, side sills and transverse members all substantially in the same planes and all interconnected by penetration of the webs of some of said members by other members extending at substantially right angles thereto, and body framing members serving as connectors for said mentioned other members and said side sills.

34. In a car underframe, side sills and transverse floor supporting members in substantially the same plane, the transverse members being removable as units by movement thereof transversely of said underframe through said side sills, and body framing members connecting the transverse members with said side sills.

35. In a car underframe, spaced side sills with apertures therein, a continuous cross-bearing member extended through said apertures and body framing members lap-

ping and being connected with said side sills and said cross-bearing member.

36. In a car underframe, spaced side sills with apertures therein, a continuous cross-bearer in the plane of and projected through said apertures beyond said side sills, and floor-nailing sills supported on the outer end portions of said cross-bearer beyond said side sills.

10 37. In a car underframe, spaced side sills and an intermediate center sill provided with aligned apertures, a continuous cross-bearer

in said apertures projecting beyond said side sills, pocket castings connecting the center sill and cross-bearer, and body framing members connecting the side sill and cross-bearer. 15

In witness whereof I have hereunto set my hand in the presence of two witnesses.
